UNITED STATES PATENT OFFICE.

CHARLES H. TURNER, OF WORCESTER, MASSACHUSETTS, ASSIGNOR TO OSGOOD
BRADLEY CAR COMPANY, OF WORCESTER, MASSACHUSETTS, A CORPORATION
OF MASSACHUSETTS.

PASSENGER-CAR.

1,205,417.

Specification of Letters Patent.

Patented Nov. 21, 1916.

Application filed April 10, 1915. Serial No. 20,525.

To all whom it may concern:

Be it known that I, CHARLES H. TURNER, a citizen of the United States, residing at Worcester, in the county of Worcester and State of Massachusetts, have invented a new and useful Passenger-Car, of which the following is a specification.

This invention relates to a passenger car and particularly to a car of the so-called "semi-convertible" type, which may be closed for cold weather use and may be largely opened for use during the warm season. In the latter case it is customary to remove the windows and to replace them by open guard frames.

It is the general object of my invention to provide an improved construction of frame and window sash so designed that the upper and lower sashes may be removed from the window frame as a single unit.

With this object in view one feature of my invention relates to the provision, in a passenger car, of a lower sash removably secured in position and of an upper sash entirely supported by the fixed lower sash.

In the preferred form of my invention the upper sash is slidably supported in upwardly extending guides secured to the fixed lower sash and provision is made for maintaining the movable upper sash in any desired vertical position with reference to the fixed sash.

A further feature of my invention relates to the provision of a single retaining means by the use of which either the fixed sash or the open guard frame may be interchangeably secured in position.

Further features of my invention relate to certain devices, arrangements and combinations of parts which will be hereinafter described and more particularly pointed out in the appended claim.

A preferred form of my invention is shown in the drawings in which—

Figure 1 is a transverse vertical section of a portion of a passenger car with my improved construction embodied therein; Fig. 2 is a detached perspective view of the sashes and guides; Fig. 3 is a perspective view of one of the guard frames; Fig. 4 is an enlarged vertical sectional view of the window frame with the sashes in position within the frame; Fig. 5 is a similar view with the guard frame in position; Fig. 6 is a horizontal sectional view through the win-

dow frame and the lower sash, taken along the line 6—6 in Fig. 4; Fig. 7 is a horizontal sectional view through the window frame and upper sash, taken along the line 7—7 in Fig. 4; Fig. 8 is a horizontal sectional view similar to Fig. 6 but showing the guard frame in operative position, and Fig. 9 is a partial horizontal sectional view similar to Fig. 6, but showing the invention as embodied in a wooden frame construction.

Referring to Fig. 1 I have shown therein a vertical transverse section of a portion of a steel frame passenger car having a floor 10, seat 11 and side wall 12. The usual window sill is indicated at 13 and it will be noted that this sill is positioned relatively low with reference to the car seat.

The car window comprises a lower sash 14 and an upper sash 15. These sashes are designed to be inserted within the window frame from the inside of the car, the lower sash engaging an abutment 16 (Fig. 6) which, in the steel construction, may be formed integral with the member 17 forming the side of the post. The sash 14 may be held against the abutment by any suitable fastening means, such for instance as the screws 18 which are inserted from the outside of the car through the abutments 16 and through the sash and which are threaded into plates 19 secured to the inside of the sash.

A pair of vertically-extending grooved guides 20 and 21 are fastened to the sash 14 upon the upper outer face thereof, said guides being fixed in position thereon by a plurality of screws 22 (Fig. 7). The guides 20 and 21 extend upwardly beyond the sash 14, as clearly shown in Fig. 2, and may be provided near their upper ends with laterally projecting lugs 23 by which they may be secured in position within the upper portion of the window frame, as by screws 24 (Figs. 4 and 7).

The abutments 16 extend upward only to the lower end of the guides 20 and 21, the guides themselves engaging narrower projections or abutments 25 (Fig. 7) which may be formed integral with any convenient portion of the window frame construction.

The upper sash 15 is slidable within the grooves of the guides 20 and 21 and may be held in adjusted vertical position therein by a spring pressed plunger 26 (Fig. 4) positioned to enter any one of a series of

recesses 27 formed in the side of the upper sash frame. Any other suitable device may be substituted for the plunger 26 for retaining the two sashes in the desired relative position.

With the construction thus far described it will be seen that the upper sash 15 is entirely supported by the lower sash 14 and that the sashes 14 and 15 are retained in position within the window frame solely by the screws 18 and 24.

It will be further noted by reference to Figs. 6 and 7 that no portions of the window frame extend into the window opening beyond the surface of the side members 17. It is thus possible to remove the upper and lower sashes and their grooved guides 20 and 21 as a unit from the window opening after the removal of the screws 18 and 24.

20 When thus removed the two sashes which are fitted within a single window opening may be stored without the possibility of separation and consequent confusion when the sashes are to be replaced in the car.

25 Furthermore the upper sash is fitted and slides within grooved guides which are permanently mounted upon the lower sash and there is thus no loss of adjustment in removing and replacing the sashes in the window openings.

It has been pointed out that the window openings extend to a point which is rather below the usual level with reference to the car floor and seat. To prevent the possibility of accidents therefrom I provide the open guard frame shown in Fig. 3. Each of these frames comprises a plurality of horizontally extending rods 30 having their ends extending through vertically spaced holes 31 in side members 31 and 32. The side members are provided with holes 33 in their outer faces corresponding in position to the screws 18. Similarly positioned threaded holes 34 are provided in the inner face of the members 31 and 32, the holes 34 being

aligned with the holes 33 and being adapted to receive the threaded ends of the screws 18.

The guard frames are inserted within the lower portion of the window opening from the inside of the car and are retained in position by the screws 18, as clearly shown in Figs. 5 and 8.

The construction shown in Fig. 9 is substantially similar to that already described, and shows the adaptation of my improvements to a wood frame construction.

In both forms it will be noted that no stops or guide strips of any sort are used inside of the sash, even the curtain groove 40 being recessed in the side face of the window frame or post. This may be accomplished by the use of the inside finish strip 41 (Fig. 6) or 42 (Fig. 9).

A very important advantage of my improved construction relates to the possibility thus attained of removing and replacing both the sash and the guard frame entirely from the inside of the car without breaking or in any way disfiguring the painted and varnished exterior surface of the car.

Having thus described my invention it will be evident that changes and modifications can be made therein by those skilled in the art without departing from the spirit and scope thereof as set forth in the claim and I do not wish to be limited to the details herein disclosed, but

What I do claim is:—

In a car, in combination, a window frame, 80 a lower sash, a pair of sash guides fixed to said sash and extending above said sash and within said frame, means for removably securing said sash and guides in said frame, and a second sash slidable in said guides.

In testimony whereof I have hereunto set my hand.

CHARLES H. TURNER.
